UNITED STATES PATENT OFFICE.

HARRY T. SHEARER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA.

CAM-GRINDER ATTACHMENT FOR GRINDING-MACHINES.

1,115,596.

Specification of Letters Patent.

Patented Nov. 3, 1914.

Application filed December 17, 1910. Serial No. 597,900.

To all whom it may concern:

Be it known that I, HARRY T. SHEARER, a citizen of the United States, residing at Waynesboro, in the county of Franklin and State of Pennsylvania, have invented certain new and useful Improvements in Cam-Grinder Attachments for Grinding-Machines, of which the following is a specification.

10 The object of my said invention is to provide an attachment for use on a well known form of grinding machine, such as the "Landis" plain or universal grinding machine, to adapt the same for grinding cams and cam-shafts, whereby the machine may be adapted for such work without alterations other than the removal of the head-stock and tail-stock and the placing of said attachment in position; and it consists in the 15 construction and arrangement of parts of the mechanism of such an attachment whereby said object is accomplished, all as will be hereinafter more fully described and claimed.

20 Referring to the accompanying drawings which are made a part hereof and on which similar reference characters indicate similar parts, Figure 1 is a fragmentary perspective view of one end of a "Landis" universal grinding machine showing my said attachment in position thereon, Fig. 2 a front elevation of said attachment as mounted upon the work-table, a central portion being broken away in order to illustrate the parts 25 on a larger scale, Fig. 3 a cross section on the dotted line 3—3 in Fig. 2, Fig. 4 a cross section on the dotted line 4—4 in Fig. 2, Fig. 5 an end elevation as seen when looking in the direction indicated by the arrow from 30 the dotted line 5—5 in Fig. 2, Fig. 6 is a detail view illustrating a form of chuck for holding the end of the master cam, Fig. 7 a similar view illustrating a form of chuck employed where the end of the cam-shaft 35 pattern carries a disk, Figs. 8 and 9 detail sections through a portion of the swinging frame illustrating the work supporting and grinding wheel truing devices respectively, Fig. 10 is a detail view illustrating a portion 40 of the chuck construction, Figs. 11 and 12 detail views illustrating the work holding devices respectively, and Fig. 13 a detail section on the dotted line 13—13 in Fig. 3.

In said drawings the portions marked A 45 represent the bed of the grinding machine,

B the work supporting table, and C the frame of the cam grinding attachment. The bed A, grinding-wheel carriage A', and the various other parts of the machine except those relating to the cam grinding attachment, are of a well known, or any approved, construction and need no special description except incidentally in describing the invention. The work-table B is any ordinary or approved form of grinding machine work-table, mounted on the bed A, as shown. The frame C of the cam grinding attachment is a heavy casting of a length sufficient to accommodate the length of the longest cam-shaft which it is desired to grind with the attachment. It consists of heavy end plates, of suitable form to carry the bearings, gear, etc., mounted thereon, connected by a web of suitable form to receive and carry the parts to be supported thereby. It is mounted to swing between suitable supports C' and C² being carried on pivots c' and c² which extend through bearings near the top of said supports and in the upper forward corners of the ends of said frame. The supports C' and C² are secured to the work-table B by clamping bolts b the heads of which engage with the T-slot in said table, in the same manner that the head-stock and foot-stock are ordinarily secured in place. Said frame is of the form in cross section best shown in Figs. 3 and 4 and has a longitudinal T-slot t in the under face of its upper portion in which are mounted a series of hangers 11 carrying bearings to support the pattern, or master cam-shaft. The bearings in said hangers 11 are formed of bronze bushings, or bushings of other suitable material, which may be made of different sizes to accommodate different sized shafts and changed as necessary to accommodate the size to be ground. A chuck C⁴ for carrying one end of the master cam-shaft and coupling it to the driving mechanism is connected to the end of a driven shaft 10 by a universal coupling as will be presently described. An adjustable bracket or standard B' is mounted on table B between the supports C' and C² and carries on its upper end a hardened steel, or glass, bearing shoe b' on the upper end of which the master cam bears in operation. Said shoe b' is secured in a suitable recess in the upper end of said standards B' by means of a clamping screw b², as best shown in Fig. 2.

The shoe shown is one of a set furnished with each attachment the bearing face of each shoe being the arc of a circle substantially corresponding to the circle of the 5 grinding wheel. The shoe in use thus bears the same relation to the master cam as the work to the grinding wheel and an accurate reproduction of the pattern is thereby insured. One shoe is provided for each inch 10 diameter of the wearing part of the wheel and in use the wheel is worn from a diameter one-half inch larger than the diameter of the circle on which the face of the shoe is formed to one-half inch smaller, when 15 the shoe is changed for the one of next smaller size. The standard B' may be adjusted along table B to any position desired between supports C' and C² by loosening the clamping nut b³, which will permit said 20 standard to be slid freely along the table B. On the end of frame C adjacent to the supports C² is formed a projecting lug 12 which normally rests against a cam 13 on the inner end of a short shaft 14, which is journaled 25 in suitable bearings in support C². Said shaft 14 is provided with a crank 15 by which it and said cam 13 thereon may be turned. A lug 16 is formed on the inner side of said crank 15 which is adapted to 30 strike against a lug 17 or a lug 18, according to which ever position said lever may stand, on the outer face of support C². As shown in Figs. 2 and 5 the lever 15 stands in its upturned position with the lug 16 in 35 contact with the lug 17 and one of the cams of the master cam-shaft M resting on the shoe b', which thus furnishes the support for the lower side of frame C on its pivots c'. When it is desired to lift said frame 40 free from shoe b', lever 15 is turned downward until its lug 17 strikes lug 18, which turns cam 13 so that, operating against lug 12, it will swing frame C forward and upward on its pivot to free the master cam 45 from said supporting shoe. This may be found necessary when the standard B', carrying said shoe, is shifted along the table B to bring said shoe into operative contact with one or the other of the cams of the 50 master cam-shaft, or when it is desired to change the shoe for a purpose previously described.

The work-holding devices are mounted on the opposite side of frame C and consist of 55 a head-stock comprising a spindle 20 at one end of said frame and adapted to support one end of the shaft constituting the work and a tail-stock carried in a suitable socket on the opposite end of said frame, and 60 formed to be longitudinally adjusted to engage with the opposite end of said work. Said tail-stock consists preferably of a cylinder 21 adapted to slide in a socket formed in a bracket 22 mounted on frame C and se- 65 cured by a top flange engaging a flange 47

on said frame and a clamping bolt 23 the head of which engages a longitudinal T-slot in the face of said frame. A spring 24 is interposed between the inner end of said cylinder and a screw-cap 25 in the outer end 70 of the socket, which spring normally tends to force the center 26, carried in the inner end of said cylinder 21, against and into the work. A lever 27 mounted on a pivot 28 on the outside of the bracket 22 extends through 75 a slot in said bracket and its inner end is formed spherical and engages with a groove in said cylinder whereby the center 26 may be withdrawn from the end of the work when desired. The head-stock spindle 20 at 80 the opposite end is journaled in bearings provided therefor in the end of frame C and carries a center 29 to engage the opposite end of the work. Between its bearings it is provided with a gear 30 adapted to 85 mesh with a gear 31 on the main driving shaft 1. (See Fig. 13). Said driving shaft 1 is provided with a driving pulley 2. A gear-wheel 32 of corresponding size to the gear wheel 30 is mounted on a journal 33 90 adjacently located and meshes with a gear-wheel 34, also of corresponding size, on the shaft of the master cam-chuck, thus insuring that the master cam and the work being 95 ground shall be driven positively and at a uniform speed. A brake consisting of two parts 35 and 36 in the form of a yoke is mounted around the chuck C⁴. Said parts 35 and 36 are suitably lined with leather or other appropriate material and secured together by clamping screws 37 by which said parts may be clamped upon the outer surface of said chuck C⁴ to secure whatever frictional resistance may be desired. The upper 100 end of part 35 is formed bifurcated and engages with a pin 39 mounted in a perforation formed in a boss c⁴, on the underside of the top of frame C. By this means the master cam is held from rotation except as positively driven by the power applied to the 105 driving gear, and all slipping, such as might be permitted by any "give", or looseness, in the gears, when the point of the master cam turns on shoe b', is thus prevented, and both the work and the master cam are held to be 110 rotated truly and uniformly by the driving gear and all slipping or vibration, or "back-lash" is prevented. Said chuck C⁴ is connected to the shaft 10 by means of a universal coupling, the chuck and shaft being 115 formed with enlarged disk flanges 70 and 71 on their adjacent ends each of which is provided with two horizontal projecting pins 72 and 73 on diametrically opposite sides, the pins of one flange being 90° from the 120 pins of the other flange. A disk 74 formed with radial notches 90° apart around its periphery is interposed between said flanges, the pins of the other flange engaging the other two notches in said disk. Said pins 125 130

are of a length not quite equal to the thickness of the disk 74 so that the chuck C⁴ is thus connected to the shaft 10 to be capable of a slight independent axial movement and 5 be freely driven thereby even though its axial line is slightly out of line with the axis of said shaft. By this means the pattern, or master cam-shaft may be supported truly in the hangers 11 and driven without 10 any binding or strain even though the axis is not in a true line with the axis of the driving shaft 10. The feature of construction is important as it is frequently difficult to adjust the axis of a pattern to true 15 axial alinement with the driving shaft.

A collar 40 is clamped upon head-stock spindle 20 by a clamping screw 41 and the outer end of arm 43 of the work engaging sleeve 42 is secured in a radial recess in one 20 side thereof by a set-screw 44. Work-steadying rests are mounted at suitable intervals apart on the front side of frame C to support and steady the work against 25 springing or vibration under action of the grinding wheel. Each of said rests consists of a casting 45 formed with side flanges 46 adapted to hook over a longitudinal rib 47 formed on the front side of said frame C. (See Fig. 8.) Said casting is formed with a 30 vertical socket in which a tubular stem 48 is mounted. Said stem is screw-threaded at its upper end and has a thumb-nut 49 thereon by which it is supported and adjusted. A holder 50 is mounted on the 35 lower end of said stem 48 formed with a recess to receive a bearing block 51 of wood or other suitable material. Each bearing block 51 is formed with a recess to receive the shaft constituting the work being 40 ground and hold it steady against springing or vibration. The recess in each block is formed on the arc of a circle substantially corresponding to the circumference of the work and a series of blocks are preferably 45 provided formed with recesses on different arcs so that one may be taken out and another of appropriate size substituted as work of different sizes is put into the machine. The holder 50 is supported by a circular, or wedge-shaped, shoe 52 interposed 50 between the surface of its rear side and the adjacent surface of frame C, which surfaces are at an angle to each other, the distance between them widening toward their lower 55 edges. Said block 52 is mounted on the lower end of a rod 53 which extends through the tubular stem 48 and is provided with a nut 54 on its upper end by which it may be 60 adjusted to slide supporting shoe 52 up or down and thus adjust the block 51 toward and away from the work. It will thus be seen that by means of the two adjustments provided by the nuts 49 and 54, the work rest may be raised or lowered or swung 65 toward or away from the work as may be

desired. To insure that the frame C will be always normally held toward the grinding wheel so as to hold the work against said grinding wheel, I mount two springs 66 in casings 67 on the inner side of supports C' and C², respectively, the inner ends of which bear against heads 68 carried on the inner face of said frame C and normally hold said frame on its pivots toward 70 said grinding wheel.

In Fig. 9 I have shown a diamondizing tool for use in turning the surface of the grinding wheel, the same consisting of the bracket 60 mounted on the front of frame C by means of a clamping bolt 61 engaging 75 with the T-slot in said frame, and comprising an arm 62 carrying a diamond socket 63 on its outer end in which the diamond is mounted said socket being adjusted by means of the adjusting screw 64 and the 80 clamping screw 65 to bring it into the proper position opposite the axis of the wheel for truing the same, as will be readily understood.

In Fig. 6 is illustrated a form of chuck C⁴ 85 used for holding the end of a master cam having a plain shaft, the same being secured in said chuck by an ordinary key-way and key, as indicated by dotted lines. In Fig. 7 is illustrated the form of chuck employed 90 where the end of the cam-shaft pattern carries a disk. In such form the disk of the shaft is secured to the disk of the chuck by 95 bolts 80.

In Fig. 11 is shown the head-stock spindle 100 20 with collar 40 clamped thereon engaged with arm 43 of a work engaging sleeve 42 of the form employed when the end of the shaft is plain. In Fig. 12 I have shown the same 105 structure except that in lieu of the form of sleeve 42 I have shown a sleeve or chuck 42^a adapted to surround the flange on the end of a cam-shaft of such a form. Other obvious modifications to adapt the attachment 110 for different forms of work may be made without departing from my said invention.

The operation is as follows: When it is desired to adapt a grinding machine for grinding cam-shafts the ordinary head-stock and tail-stock are removed and the bracket 115 B' and the supports C' and C² are placed in position on the table B and the frame C, carrying the mechanism herein described, is swung on the pivots c' between said supports. A pattern of the work to be ground, 120 preferably formed of hardened steel, is mounted in position in the hangers 11 on the underside of frame C, one end of said pattern being connected to chuck C⁴ and thus coupled to the pattern driving shaft 10 through the medium of the universal coupling before described. The work to be ground is then mounted between the centers 29 and 26 carried by the head-stock and tail-stock, respectively, on the opposite side of 125 130

said frame, the end of the work adjacent to the head-stock being connected to the sleeve 42, or collar 42^a, according to the form of the end of the work, and thus coupled to the 5 head-stock to be driven thereby. While the parts are being adjusted in position and prepared for work the frame C is preferably held forward and supported on the cam 13 with the pattern free from the shoe b'. The 10 bracket B' is then adjusted to bring said shoe b' in line with the cam of the pattern corresponding to the cam of the work to be ground. The lever 15 is then turned to lower said frame on its pivots until the cam 15 of the master rests upon said shoe as before described. The grinding wheel is then brought into position to operate upon the cam to be ground and the machine started in operation. The work proceeds until the 20 work has been ground to a form to correspond with the pattern, when the shoe supporting the frame C will support the work in contact with the grinding wheel during its entire revolution thus indicating that the 25 desired form has been attained. The frame C may then be swung on its pivot by means of the lever 15 and cam 13 to lift the pattern free from the supporting shoe, which is then slid along table B into position to be in line 30 with the cam on the pattern corresponding with the next cam to be ground, when the frame is again turned down and the work proceeds as before described. After the several cams of one cam-shaft have been 35 ground, the tail-stock center 26 may be disengaged from its end of the work, by means of lever 27 and the opposite end then disengaged from the head-stock and the work removed and another shaft put in place and 40 the same process repeated. During the grinding operation the brake on the chuck C^a carrying the pattern is adjusted to maintain sufficient frictional resistance to prevent any slipping, or movement of one part of 45 the work faster than another, such as might occur when the pattern turns over its point on the shoe b' which would cause the gearing to "run" slightly to take up any slight looseness that might be in the gearing except for such a brake, as will be readily understood. The master cams or patterns, 50 are provided of standard sizes for different characters of work. If it is desired to make a special cam or adapt the machine for special work it is only necessary to make a master, or pattern, of the special form or character desired. By reference, especially to Fig. 4, it will be noted that the work at 55 all times bears the same relation to the grinding wheel that the pattern does to the curved bearing surface of shoe b'. It will also be noted that the axis of the work and the axis of the pattern are both in the arc of a circle of which the pivotal axis of the 60 frame C is the center so that said corre- 65

sponding relationship between cam and shoe, and work and wheel, is always maintained regardless of any swinging movement of said frame. The accurate grinding of the work to correspond to the pattern is thus insured. 70

Having thus fully described my said invention, what I claim as new and desire to secure by Letters Patent, is:

1. A cam grinding attachment for grinding machines comprising a swinging frame mounted on the work-table of the machine, work-holding devices on said swinging frame, pattern holding devices also on said swinging frame, gearing connecting said work-holding and pattern holding devices for driving the work and pattern uniformly, said pattern and work-holding devices being arranged with their axes in the arc of a circle the center of which is the pivotal center of said frame, substantially as set forth. 75 80 85

2. A cam grinding attachment for grinding machines comprising supports mounted on the work-table of the machine, a frame mounted to swing on pivots between said supports, a head-stock and tail-stock for supporting the work mounted on one side of said frame below the line of its pivots, bearings carried on the other side of said frame in a line below its pivots, a master or pattern shaft mounted in said bearings, a shoe mounted on an adjustable support on said table and formed with a curved bearing surface corresponding substantially to the curvature of the grinding wheel, a chuck for engaging said pattern mounted on the end of a shaft journaled in said pivoted frame, a train of gearing connecting said shaft with the shaft of the head-stock, and driving gear connected with said train of gearing, substantially as set forth. 90 95 100 105

3. A cam grinding attachment for grinding machines comprising supports mounted on the work-table of the machine, a frame mounted between said supports on pivots, a master or pattern shaft mounted in suitable bearings on said frame, a bearing shoe supported on the machine table and adapted to contact with the pattern, a pattern driving shaft journaled in bearings in said frame substantially in axial alignment with said pattern shaft, a chuck on the inner end of said shaft connected therewith by a universal coupling and adapted to connect with the end of said pattern shaft, work-holding devices also mounted on said frame, and driving gear for driving said work-holding devices and said pattern driving shaft simultaneously, substantially as set forth. 110 115 120 125

4. A cam grinding attachment for grinding machines comprising a swinging frame, work-holding devices mounted on said swinging frame one of which is journaled to be driven, pattern holding devices axially 129

- spaced from said work holding devices also mounted on said swinging frame adjacent to the head-stock driving shaft, a chuck on said pattern driving shaft for receiving and holding the pattern, a train of gearing between the pattern driving shaft and the head-stock driving shaft for driving the same uniformly, and a main driving shaft connected with said train of gearing, substantially as set forth.
5. A cam grinding attachment for grinding machines comprising a frame mounted to swing on pivots above the work-table of the machine, work-holding devices mounted on said frame, a pattern mounted in bearings also carried by said frame, a pattern driving shaft journaled in bearings in said frame, a chuck engaged with said pattern and coupled to the pattern driving shaft by a universal joint to permit slight variation between the axial alinement of the driving shaft and the pattern, said coupling comprising a disk interposed between disks on the adjacent ends of the shaft and a chuck formed with radial notches with which horizontal pins projecting from the disk of the shaft and from the disk of the chuck are adapted to engage, and gearing for driving the pattern and the work, substantially as set forth.
10. A cam grinding attachment for grinding machines comprising a frame mounted to swing on horizontal pivots between suitable supports, work-holding devices on said frame, a pattern journaled on said frame, the axes of said work-holding devices and pattern being in the arc of a circle the center of which is the axial line of the pivots of said frame, a bearing shoe mounted on the table against which the pattern is adapted to rest, the bearing face of said shoe being formed in the arc of a circle of substantially the same diameter as the circle of the grinding wheel, substantially as set forth.
15. A cam grinding attachment for grinding machines comprising a frame mounted to swing on horizontal pivots between suitable supports, work-holding devices on said frame, a pattern journaled on said frame, the axes of said work-holding devices and pattern being in the arc of a circle the center of which is the axial line of the pivots of said frame, a bearing shoe mounted on the table against which the pattern is adapted to rest, the bearing face of said shoe being formed in the arc of a circle of substantially the same diameter as the circle of the grinding wheel, substantially as set forth.
20. A cam grinding attachment for grinding machines comprising a frame mounted to swing on horizontal pivots between suitable supports, work-holding devices on said frame, a pattern journaled on said frame, the axes of said work-holding devices and pattern being in the arc of a circle the center of which is the axial line of the pivots of said frame, a bearing shoe mounted on the table against which the pattern is adapted to rest, the bearing face of said shoe being formed in the arc of a circle of substantially the same diameter as the circle of the grinding wheel, substantially as set forth.
25. A cam grinding attachment for grinding machines comprising a frame mounted to swing on horizontal pivots between suitable supports, work-holding devices on said frame, a pattern journaled on said frame, the axes of said work-holding devices and pattern being in the arc of a circle the center of which is the axial line of the pivots of said frame, a bearing shoe mounted on the table against which the pattern is adapted to rest, the bearing face of said shoe being formed in the arc of a circle of substantially the same diameter as the circle of the grinding wheel, substantially as set forth.
30. A cam grinding attachment for grinding machines comprising a swinging frame, work-supports on said frame, a pattern on said frame, a bearing on the work-table for said pattern to rest upon, gearing for driving the pattern and the work and a brake for engaging one of the driven parts and hold the same under tension, whereby any slipping or "back-lash" is prevented during the operation of grinding, substantially as set forth.
35. A cam grinding attachment for grinding machines comprising a swinging frame, work-supports on said frame, a pattern on said frame, a bearing on the work-table for said pattern to rest upon, gearing for driving the pattern and the work and a brake for engaging one of the driven parts and hold the same under tension, whereby any slipping or "back-lash" is prevented during the operation of grinding, substantially as set forth.
40. A cam grinding attachment for grinding machines comprising a swinging frame, work-supports on said frame, a pattern on said frame, a bearing on the work-table for said pattern to rest upon, gearing for driving the pattern and the work and a brake for engaging one of the driven parts and hold the same under tension, whereby any slipping or "back-lash" is prevented during the operation of grinding, substantially as set forth.
45. A cam grinding attachment for grinding machines comprising a swinging frame, work-supports on said frame, a pattern on said frame, a bearing on the work-table for said pattern to rest upon, gearing for driving the pattern and the work and a brake for engaging one of the driven parts and hold the same under tension, whereby any slipping or "back-lash" is prevented during the operation of grinding, substantially as set forth.
50. A cam grinding attachment for grinding machines comprising a swinging frame, work-holding devices thereon, a pattern shaft mounted in bearings carried by said frame, a driving shaft, a chuck coupled to said driving shaft and to said pattern shaft, a brake comprising friction shoes surrounding said chuck and clamped thereto by clamping screws, and means for holding said brake from turning with said chuck, whereby said pattern driving means is held against any movement except that caused by the driving mechanism, substantially as set forth.
55. A cam grinding attachment for grinding machines comprising a pivoted frame, work-holding devices mounted on said frame, a pattern mounted in bearings axially spaced from said work-holding devices, a shoe mounted in a support on the machine table against which the pattern is adapted to rest, the bearing face of said shoe being formed in the arc of a circle of substantially the same diameter as the grinding wheel, substantially as set forth.
60. A cam grinding attachment for grinding machines comprising a pivoted frame, work-holding devices mounted on said frame, a pattern mounted in bearings axially spaced from said work-holding devices, a shoe mounted in a support on the machine table against which the pattern is adapted to rest, the bearing face of said shoe being formed in the arc of a circle of substantially the same diameter as the grinding wheel, substantially as set forth.
65. A cam grinding attachment for grinding machines comprising a pivoted frame, work-holding devices mounted on said frame, a pattern mounted in bearings axially spaced from said work-holding devices, a shoe mounted in a support on the machine table against which the pattern is adapted to rest, the bearing face of said shoe being formed in the arc of a circle of substantially the same diameter as the grinding wheel, substantially as set forth.
70. A cam grinding attachment for grinding machines comprising a frame mounted to swing on horizontal pivots between suitable supports, work-holding devices on said frame, a pattern journaled on said frame, the axes of said work-holding devices and pattern being in the arc of a circle the center of which is the axial line of the pivots of said frame, a bearing shoe mounted on the table against which the pattern is adapted to rest, the bearing face of said shoe being formed in the arc of a circle of substantially the same diameter as the circle of the grinding wheel, substantially as set forth.
75. A cam grinding attachment for grinding machines comprising a frame mounted to swing on horizontal pivots between suitable supports, work-holding devices on said frame, a pattern journaled on said frame, the axes of said work-holding devices and pattern being in the arc of a circle the center of which is the axial line of the pivots of said frame, a bearing shoe mounted on the table against which the pattern is adapted to rest, the bearing face of said shoe being formed in the arc of a circle of substantially the same diameter as the circle of the grinding wheel, substantially as set forth.
80. A cam grinding attachment for grinding machines comprising a frame mounted to swing on horizontal pivots between suitable supports, work-holding devices on said frame, a pattern journaled on said frame, the axes of said work-holding devices and pattern being in the arc of a circle the center of which is the axial line of the pivots of said frame, a bearing shoe mounted on the table against which the pattern is adapted to rest, the bearing face of said shoe being formed in the arc of a circle of substantially the same diameter as the circle of the grinding wheel, substantially as set forth.
85. A cam grinding attachment for grinding machines comprising a frame mounted to swing on horizontal pivots between suitable supports, work-holding devices on said frame, a pattern journaled on said frame, the axes of said work-holding devices and pattern being in the arc of a circle the center of which is the axial line of the pivots of said frame, a bearing shoe mounted on the table against which the pattern is adapted to rest, the bearing face of said shoe being formed in the arc of a circle of substantially the same diameter as the circle of the grinding wheel, substantially as set forth.
90. A cam grinding attachment for grinding machines comprising a swinging frame, a head-stock and tail-stock mounted at opposite ends of said frame, said frame being formed with a longitudinal projecting flange, work-rests adapted to support the work between said head-stock and tail-stock hung upon said flange, means for adjusting said work-rests to adapt them for work of different sizes, a pattern also on said swinging frame, a supporting shoe for said pattern, and gearing for driving both the work and the pattern, substantially as set forth.
95. A cam grinding attachment for grinding machines comprising a swinging frame, a head-stock and tail-stock mounted at opposite ends of said frame, said frame being formed with a longitudinal projecting flange, work-rests adapted to support the work between said head-stock and tail-stock hung upon said flange, means for adjusting said work-rests to adapt them for work of different sizes, a pattern also on said swinging frame, a supporting shoe for said pattern, and gearing for driving both the work and the pattern, substantially as set forth.
100. A cam grinding attachment for grinding machines comprising a swinging frame, a head-stock and tail-stock mounted at opposite ends of said frame, said frame being formed with a longitudinal projecting flange, work-rests adapted to support the work between said head-stock and tail-stock hung upon said flange, means for adjusting said work-rests to adapt them for work of different sizes, a pattern also on said swinging frame, a supporting shoe for said pattern, and gearing for driving both the work and the pattern, substantially as set forth.
105. A cam grinding attachment for grinding machines comprising a swinging frame, a head-stock and tail-stock mounted on said frame for supporting the work, a pattern mounted on said frame, a stationary bearing for said pattern to rest upon, gearing for driving both the work and the pattern and a clamping sleeve adapted to be clamped upon one end of the work and connected with a collar clamped upon the head-stock, and said collar, substantially as set forth.
110. A cam grinding attachment for grinding machines comprising a swinging frame, a head-stock and tail-stock mounted on said frame for supporting the work, a pattern mounted on said frame, a stationary bearing for said pattern to rest upon, gearing for driving both the work and the pattern and a clamping sleeve adapted to be clamped upon one end of the work and connected with a collar clamped upon the head-stock, and said collar, substantially as set forth.
115. A cam grinding attachment for grinding machines comprising a swinging frame, a head-stock and tail-stock for carrying the work mounted on said frame, said head-stock being journaled to be driven in bearings and said tail-stock being mounted to be adjusted longitudinally on said frame, a pattern also carried by said frame axially spaced from the work, a stationary rest against which said pattern is adapted to bear, and means for driving both the pattern and the head-stock, substantially as set forth.
120. A cam grinding attachment for grinding machines comprising a swinging frame, a head-stock and tail-stock for carrying the work mounted on said frame, said head-stock being journaled to be driven in bearings and said tail-stock being mounted to be adjusted longitudinally on said frame, a pattern also carried by said frame axially spaced from the work, a stationary rest against which said pattern is adapted to bear, and means for driving both the pattern and the head-stock, substantially as set forth.
125. A cam grinding attachment for grinding machines comprising a swinging frame, a head-stock and tail-stock for carrying the work mounted on said frame, said head-stock being journaled to be driven in bearings and said tail-stock being mounted to be adjusted longitudinally on said frame, a pattern also carried by said frame axially spaced from the work, a stationary rest against which said pattern is adapted to bear, and means for driving both the pattern and the head-stock, substantially as set forth.
130. A cam grinding attachment for grinding machines comprising a swinging frame, a head-stock and tail-stock for carrying the work mounted on said frame, said head-stock being journaled to be driven in bearings and said tail-stock being mounted to be adjusted longitudinally on said frame, a pattern also carried by said frame axially spaced from the work, a stationary rest against which said pattern is adapted to bear, and means for driving both the pattern and the head-stock, substantially as set forth.

projecting flange on one side, a head-stock journaled in bearings in said frame, a tail-stock mounted to engage with said longitudinal flange and secured to be adjusted 5 alongside said flange to accommodate work of different lengths, a pattern mounted on said frame, a stationary rest against which said pattern is adapted to bear, and gearing for driving both the pattern and headstock, substantially as set forth.

15. A cam grinding attachment for grinding machines comprising a swinging frame mounted on the work-table of the machine, a longitudinally projecting flange on the face 15 of said frame adjacent to the grinding wheel, a tail-stock mounted on said frame to engage with said flange and secured to be adjusted longitudinally, work rests also mounted to engage with said flange and be 20 adjusted longitudinally, a head-stock spindle journaled in bearings in the end of said frame in line with said tail-stock, a pattern mounted on the opposite side of said frame, a stationary rest for said pattern, and gearing 25 for driving both the pattern and the head-stock, substantially as set forth.

16. A cam grinding attachment for grinding machines comprising a pivoted frame mounted on the work-table of the machine, 30 work-holding devices on the side of said

frame adjacent to the grinding wheel, bearings adjustably hung on the opposite side of said frame, means for adjusting said bearings, a pattern shaft journaled in said bearings, a rest for said pattern to bear 35 against, and gearing for driving the pattern and work, substantially as set forth.

17. A cam grinding attachment for grinding machines comprising a pivoted frame mounted on the work-table of the machine, 40 work-holding devices on the sides of said frame adjacent to the grinding wheel, said frame being formed with a longitudinal T-groove in an overhanging part on its opposite side, hangers mounted by means of 45 clamping bolts in said groove and formed with bearings in their lower ends, a pattern mounted in said bearings, a pattern driving shaft coupled to said pattern, and gearing for driving said pattern driving shaft 50 and the work-holding devices, substantially as set forth.

In witness whereof, I, have hereunto set my hand and seal at Waynesboro, Pennsylvania this 28th day of November, A. D. 55 nineteen hundred and ten.

HARRY T. SHEARER. [L.S.]

Witnesses:

J. ARTHUR KNAPE,
CHAS. B. CLAYTON.
